UNITED STATES PATENT OFFICE.

CHARLES V. KNOWLES, OF SOMERVILLE, NEW JERSEY, ASSIGNOR TO
EDWIN HOLMES, OF NEW YORK, N. Y.

ELECTRICAL INDICATOR FOR RUDDERS.

SPECIFICATION forming part of Letters Patent No. 495,047, dated April 11, 1893.

Application filed February 16, 1892. Serial No. 421,679. (No model.)

To all whom it may concern:

Be it known that I, CHARLES V. KNOWLES, of Somerville, county of Somerset, and State of New Jersey, have invented a new and useful Improvement in Electrical Indicators for Rudders, of which the following is a specification.

This invention relates to devices for indicating the position of a ship's rudder and it consists of an indicator which may be placed in any desired position on a vessel and having a connection with the rudder whereby the movements of the rudder will close an electric circuit and cause an indicator pointer to move over a dial to show the degree of angle of the rudder.

I will describe a device embodying my improvement and then point out the novel features in claims.

In the accompanying drawings, Figure 1 is an interior view of an indicator embodying my invention, showing the electric circuit in connection with a steering gear. Fig. 2 is a front view of the indicator. Fig. 3 is a detail of an escapement mechanism employed. Fig. 4 is a side view of circuit closer employed. Fig. 5 is a front view thereof. Fig. 6 is a section on the line 6, 6, of Fig. 5.

Referring by letters and figures to the drawings, A designates the indicator case of any desired material having on its front a series of figures arranged in an arc of a circle a. The zero mark is in the center of an arc and the figures increase in value from the zero mark in opposite directions.

A' A² designate electro-motive devices or electro-magnets supported on brackets a', of insulating material, within the case A.

B² and B³ show electro-motive devices arranged adjacent to and co-acting with the respective devices A' A².

An armature A³ coacts with the electro motive device A' B² and an armature A⁴ coacts with the electro-motive devices A² B³. These armatures are respectively pivoted near one end to a fixed portion of the case A, as at a², and have a counterbalance, here shown as a weight at the outer end. The armature A³ has a link connection a³ with an escapement A⁵, and the armature A⁴ has a link connection a⁴ with an escapement A⁶. Each

escapement is fulcrumed at about its center on a shaft affixed to the base of the case A.

B B' designate escapement wheels both rigidly mounted on a shaft b having bearings in the case A, and extended outward through the front of the case where it is provided with a pointer B⁶ designed to move its end over the indicating marks a.

The escapement wheels B B' have their teeth pitched in opposite directions, and each wheel co-acts with one of the escapements. As here shown the escapement A⁵ co-acts with the wheel B' and the escapement A⁶ co-acts with the wheel B. Obviously when the electro-motive device A' is energized its armature will be drawn toward it and thus rock the escapement A⁵ which will move its wheel one half step and consequently move the pointer one half step in one direction. Upon de-energizing the electro-motive device A' and energizing the electro-motive device B² the armature A³ will be drawn in the opposite direction and complete the one step of the escapement wheel and pointer. Conversely, when the electro-motive devices A² B³ are energized and de-energized the armature A⁴ will be moved to cause the escapement A⁶ to move its wheel, which will cause the pointer to move in the opposite direction one step at a time, as before indicated.

The several electro-motive devices are energized through the movements of the vessel's rudder operating to close an electric circuit in a manner which I will now explain.

C designates a rudder head or post having the tiller C' which, in this example, carries two series of metal contact points c. The contact points of each series are arranged in the arc of a circle and correspond in number to the number of points on the face of the case A.

C² C³ C⁴ C⁵ designate yielding contact strips. These contact strips are of resilient metal secured at one end to a hanger C⁶ depending from a portion of the vessel, directly above the path of the points c. And C⁷, C⁸, C⁹, C¹⁰, designate contact strips also secured to the hanger C⁶. These last named contact strips are of resilient metal, and are arranged with in the contact strips C² C³ C⁴ C⁵, respectively, so that the strip C⁷ may be moved into contact with the strip C², the strip C⁸ with the

strip C³, the strip C⁹ with the strip C⁴, and the strip C¹⁰ with the strip C⁵. A block D is fulcrumed to the hanger C⁶ between the projected ends of the contact strips C⁸ C⁹, and a block 5 D' is fulcrumed to the hanger between the projected ends of the contact strips C⁷ C¹⁰. The upper ends of these blocks D D', consist of insulating material, but I prefer the lower pointed ends to be of metal as they are de-
10 signed to be engaged by the projections c. From the contact strip C⁷, a wire 1 leads to the electro-magnet B², and a wire 2 leads from the contact strip C⁸ to the electro-motive de-
15 vice A'. From the contact strip C¹⁰ a wire 3 leads to the electro-motive device A². From the contact strip C⁹ a wire 4 leads to the elec-
20 tro motive device B³. A wire 5 connects the several electro-motive devices with one pole of a source of electricity or battery E and from
25 the other pole of the battery a wire 6 leads to the several contact strips C², C³, C⁴, C⁵.
By the construction described it will be seen that when the tiller C' is moved in one direction, say in the direction indicated by the ar-
30 25 row, a projection c on the segment F will tilt the block D' and cause it to close the circuit through the contact strips C⁵, C¹⁰ and energize the electro-motive devices A². This will draw the armature A⁴ down and operate the pointer
35 B⁶ one half point. When the projection c on the segment F shall have passed the block D' a projection c on the segment F' will tilt the block D and cause it to close the circuit through the contacts C⁴ C⁹, and energize the
40 35 electro-motive device B³ to draw the armature A⁴ upward and complete the movement of the pointer B⁶. Of course a continued movement of the tiller in the same direction will success-
45 40 35 ily energize and de-energize the electro- motive devices A² B³ and move the pointer and when the tiller is moved in the other direction, the opposite electro-motive devices will operate the pointer.

Having described my invention, what I claim, and desire to secure by Letters Patent, 45 is—

1. The combination with a vessel's rudder, of a source of electricity, electro-motive devices yielding contact strips arranged adjacent to the rudder head or tiller, wires be- 50 tween said contact strips and the electro motive devices, projections carried by the rudder head or tiller adapted to close a circuit be-
tween contact strips, and a wire between cer-
tain of the strips and one pole of the source 55 of electricity and a wire leading from the other pole thereof to the electro-motive, de-
vices, substantially as specified.

2. The combination with a vessel's rudder, of a source of electricity, two sets of electro- 60 motive devices, a pointer or indicator, connec-
tions between the source of electricity and the electro-motive devices, a series of contact points carried by the rudder for closing a cir-
cuit through one set of electro-magnets to 65 move the pointer or index in one direction and another series of contact points carried by the rudder for closing a circuit through the other set of electro-motive devices to move the pointer or indicator in the opposite direction, 70 substantially as specified.

3. In an indicator for a ship's rudder, the combination with the indicator and the elec-
trical connections, of the circuit closer comprising the resilient contact strips, the tilting 75 blocks and the projections carried by a por-
tion of the ship's rudder, substantially as specified.

In testimony whereof I have signed my name to this specification in the presence of 80 two subscribing witnesses.

CHARLES V. KNOWLES.
